UNITED STATES PATENT OFFICE.

JOHN HAVILAND, OF BOSTON, MASSACHUSETTS.

THILL-COUPING.

SPECIFICATION forming part of Letters Patent No. 289,413, dated December 4, 1883.

Application filed September 19, 1883. (No model.)

To all whom it may concern:

Be it known that I, JOHN HAVILAND, of Boston, in the county of Suffolk, of the Commonwealth of Massachusetts, have invented 5 a new and useful Improvement in Carriage-Shaft Connections; and I do hereby declare the same to be described in the following specification and represented in the accompanying drawings, of which—

10 Figure 1 is a side view, Fig. 2 a top view, Fig. 3 a bottom view, and Fig. 4 a longitudinal section, of a shaft-connection of my improved kind, the nature of my invention being defined in the claims hereinafter presented.

15 In such drawings, A denotes the axle-clip, constructed with ears *a a*, projecting from it, as shown. Through these ears there extends a screw-bolt, B, screwed into one of them, or a nut, C; or the said ears, instead of having 20 such a bolt, may be connected by a pivotal pin extending from one to the other of them and properly fixed in or to them. A metallic spring, D, goes around the bolt between the two ears and extends back therefrom in manner as represented in Fig. 4. There is placed 25 between the lips *b b* of such spring and to project from them rearward a yielding elastic plate, *c*, of leather or vulcanized india-rubber.

The joint-piece E, to which the carriage 30 shaft or thill is to be affixed, is provided with a jaw, *d*, in one piece with it, and also with another jaw, *e*, hinged to it, both of such jaws being recessed to span the spring and the leather or rubber plate in manner as represented. Furthermore, a headed screw, F, goes down through the jaw *d* and the plate *c* and screws into the movable jaw *e*. This screw serves to clamp the jaws on the spring, and the rubber or leather plate, and the spring 40 on the pivotal bolt, and to do this from time to time as the spring and the bolt may become worn. By having the screw-head above the jaws or on the upper of them, not only can access readily be had to it for revolving it, but

the weight of the screw tends to keep the 45 screw in place. Were the lower jaw hinged at its rear instead of its front part to the other jaw, the clamping-screw would have to extend upward through such lower jaw, in which case the head of the screw would be underneath such lower jaw, from which it will be seen that the weight of the screw would aid in loosening the screw and rendering it liable to work out of the jaw. Were the lips of the 50 spring extended to the rear ends of the jaws without having between the said lips the yielding plate of leather or rubber, there would necessarily be an open space between the said lips, into which space dirt or frozen matter would be liable to collect and impede 55 the action of the spring. The yielding plate not only fills the space, and thus prevents any such collections, but is advantageous in other respects.

I claim—

1. The described shaft joint-piece provided with the fixed jaw and the hinged jaw, and also with the screw arranged with and adapted to them, as represented, in combination not only with the clip provided with ears and a screw-bolt or pivotal pin, but with the lipped metallic spring extending around such bolt or pin and between the jaws, all being substantially as set forth.

2. The shaft joint-piece provided with the 75 fixed jaw and the hinged jaw, and also with the clamp-screw arranged with and adapted to them, as represented, in combination not only with the clip having ears and a screw-bolt or pivotal pin, but with the lipped metallic spring and the yielding or elastic plate arranged with such jaws and pin, substantially 80 as set forth.

JOHN HAVILAND.
